UNITED STATES PATENT OFFICE

2,636,274

ALIGNING DEVICE

Stewart E. Marsh, Windgap, Pa.

Application February 5, 1951, Serial No. 209,439

1 Claim. (Cl. 33—85)

1

This invention pertains to new and useful improvements in aligning devices and has for its primary object a means for determining the error or deviation of intermediate portions of a masonry wall relative to the ends thereof.

An important object of this invention is to provide a wall aligning device having a means for leveling a course of a masonry wall, thereby preventing sag in the center of the wall.

Important features of this invention are to provide a sighting level simulating a telescope, a target having cross-hairs for alignment with the sighting level and intermediate longitudinally adjustable set of cross-hairs for alignment with the sighting and target levels.

These, together with various ancillary features and objects of the invention, which will later become apparent as the following description proceeds, are attained by the present invention, a preferred embodiment of which is illustrated, by way of example only, in the accompanying drawings, wherein:

Figure 1 is a front vertical view of a portion of a masonry wall and showing the application of the instant invention thereto;

Figure 2 is a top plan view of Figure 1;

Figure 3 is a fragmentary vertical view showing a section through the sighting block as taken along the plane of the section line 3—3 of Figure 2;

Figure 4 is a vertical sectional side view taken along the plane of the section line 4—4 of Figure 1;

Figure 5 is a vertical sectional side view taken along the plane of the section lines 5—5 of Figure 1; and

Figure 6 is a vertical sectional side view taken along the plane of the section lines 6—6 of Figure 1.

Referring now to the accompanying drawings, wherein like numerals indicate similar parts throughout the various views, it will be evident that the numeral 10 denotes a portion of a masonry wall constructed in a conventional manner of a plurality of courses 12 of building block, brick or the like.

It is well known that the task of maintaining each brick in a single course at the same level or what amounts to the same thing, a plurality of levels or horizontal courses one above the other is indeed very arduous. Heretofore, as seen in the patent to W. H. Batchler, No. 2,505,935, the method of aligning intermediate blocks in a course was effected by tautly stretching a guide line between the ends of the course. This method could offer no assurance that a course

2

was level, but merely that all points along the course were in the same line; even the latter could be erroneous if a slight amount of slack or sag occurred in the guide line.

5 To alleviate these disadvantages, the instant invention provides a pair of guide line holders or end blocks 14 and 16 having a guide line 15 stretched therebetween.

Block 14 has a substantially L-shaped contour 10 but one leg diverges inwardly, as at 20, for a purpose believed to be well-known but nevertheless to be explained in subsequent description. The transverse leg 18 also contains a medial slot 22 cutting through the central longitudinal cross 15 section of the same. The leg 24 is provided at its upper surface with a longitudinal recess 26 opening on both ends of the leg.

With the exception that its construction is reversed, the block 16 is identical, having a longitudinal leg 28 with a recess 30 and an inwardly divergent transverse leg 32 with a slot 34. The reason for making one block the reverse of the other is clearly seen from Figures 1 and 2, where the blocks are illustrated in position on the masonry wall.

In either of the blocks, as 14, there is slidably emplaced in the recess 26 a sighting means 36 comprising an elongated body 38 having open ends and being constructed of some suitable material. At one end of this body there is a window gauge 40 having, thereon a plurality of graduations as at 42. At this same end and disposed on the top side 24 of the body 38 is a spirit level 46 of a known and conventional construction. Separating the level 46 from the interior of the body is a glass pane and immediately below the same is a reflecting surface 50 mounted on an angular support 52.

At the opposite end of the body 38 is an eyepiece 54 of conventional nature and which, if desired, could assume the form of a telescopic lens. It will now be evident that by looking into the eyepiece 54, it will be possible to see both the spirit level 46 and the graduated window gauge 40.

45 Since for the purpose of discussion, the block 14 has been chosen to receive the sighting means, the block 16 will be assumed to receive the target means 56. It should be understood that either block 14 or 16, could, if desired, receive either the target or sighting devices. At any rate, the target means 56 consists of an elongated solid block 58 slidably received in the recess 30 and having inscribed on one end 60 a set of cross-hairs, as 62.

55 From the foregoing, it will be apparent that

in the process of constructing the wall 10, it will be necessary to test the height of each block in a course whereby the latter may be adjusted to provide a horizontal or level wall. With the guide line 15 stretched tautly, the sighting block 14 is placed on the corner of the wall adjacent any desired course to be tested. Since the legs are constructed at an acute angle, a firm fit is assured. By viewing the reflecting surface in the eyepiece, the spirit level may be observed whereby if the block 14 is adjusted, the same will become level. Now, by viewing the cross-hairs 62 of the target block 16 through the eyepiece, the target may be brought into level relationship with the sight. Now the ends, at least, of the 15 guide line 15 will also be level. However, intermediate the ends the line may tend to slack or sag. This invention, therefore, provides a means to alleviate this disadvantage.

Accordingly, a U-shaped center block 64 having a central recess 66 which is adapted to slidably fit over the top of a masonry block is provided, as seen in Figure 5. In the outwardly extending legs 68 of the center block is an aligning means consisting of an aperture 70 within which is disposed a set of cross-hairs 72. Furthermore, a small hole 74 is provided in the crotch between the outward leg and the central recess for reception of the guide line 15.

Therefore, once the sight and target blocks 30 are arranged level, it only remains necessary to place the intermediate aligning block 64 at the desired point of test along the course whereby the lateral and vertical deviation of this portion of the course or wall can be determined and accordingly corrected.

From the foregoing, the construction and operation of the device will be readily understood and further explanation is believed to be unnec-

10

4
essary. However, since numerous modifications and changes will readily occur to those skilled in the art after a consideration of the foregoing specification and accompanying drawings, it is not desired to limit the invention to the exact construction shown and described, for all suitable modifications and equivalents may be resorted to, falling within the scope of the appended claim.

Having described the invention, what is claimed as new is:

A masonry wall aligning device comprising, a pair of end blocks for mounting on a wall, a guide line stretched between said end blocks, and an elongated center block for mounting transversely on the wall between the end blocks and including a projecting end portion having an aligning aperture therein, said center block further having an elongated recess in its lower portion for the reception of the wall and still further having a hole therethrough for the passage of the line, said hole communicating with the recess for the insertion and removal of the line.
